[57] CLAIM

The ornamental design for a fire ladder rung, as shown and described.

DESCRIPTION

FIG. 1 is a perspective view of a fire ladder rung showing our new design, it being understood that the broken lines are for illustrative purposes only;
FIG. 2 is a front elevational view thereof;
FIG. 3 is a top plan view thereof;
FIG. 4 is a rear elevational view thereof;
FIG. 5 is a bottom plan view thereof; and
FIG. 6 is an end elevational view thereof.
